US0D1047693S

(12) **United States Design Patent** (10) **Patent No.:** **US D1,047,693 S**
(45) **Date of Patent:** **** Oct. 22, 2024**

(54) **METAL BOTTLE**

(71) Applicant: **Ball Corporation**, Broomfield, CO (US)

(72) Inventors: **Linda A. Hines**, Westminster, CO (US);
Matthias van de Liefvoort, Louisville, CO (US)

(73) Assignee: **Ball Corporation**, Westminster, CO (US)

(**) Term: **15 Years**

(21) Appl. No.: **29/737,485**

(22) Filed: **Jun. 9, 2020**

(51) LOC (14) Cl. **09-03**

(52) U.S. Cl.

USPC **D9/500**; D9/549; D9/558

(57) **CLAIM**

The ornamental design for a metal bottle as shown and described.

DESCRIPTION

FIG. 1 is a front perspective view of a metal bottle;
FIG. 2 is a front elevation view thereof;
FIG. 3 is a top plan view thereof;
FIG. 4 is a bottom plan view thereof;
FIG. 5 is a cross-sectional view thereof taken at the line 5-5 in FIG. 3;
FIG. 6 is a front perspective view of a metal bottle according to another embodiment;
FIG. 7 is a front elevation view of the metal bottle of FIG. 6;
FIG. 8 is a top plan view of the metal bottle of FIG. 6;
FIG. 9 is a bottom plan view of the metal bottle of FIG. 6; and,
FIG. 10 is a cross-sectional view of the metal bottle taken at the line 10-10 in FIG. 8.
The dashed lines showing portions of the metal bottle depict environment and form no part of the claimed design.

1 Claim, 8 Drawing Sheets
